(Cl. D44—29)

FIG. 2.

FIG. 3.

FIG. 4.

FIG. 6.

FIG. 5.

To all whom it may concern:

Be it known, that I, Nathan W. Roop, a citizen of the United States, residing at Columbus, in the county of Franklin and State of Ohio, have invented a new, original, and ornamental Design for a Tableware Drying Rack or Similar Article, of which the following is a specification, reference being had to the accompanying drawings, forming a part thereof.

Fig. 1 is a perspective view of a tableware drying rack or similar article showing my new design;

Fig. 2 is a bottom plan view;

Fig. 3 is a side elevational view;

Fig. 4 is an end elevational view;

Fig. 5 is a similar view looking toward the opposite end of the tableware drying rack or similar article; and

Fig. 6 is an enlarged fragmentary vertical sectional

view taken through one of the corner regions of the tableware drying rack or similar article along the line 6-6 of Fig. 1.

The side of the tableware drying rack or similar article not disclosed in the drawings is identical in appearance to the side thereof shown in Fig. 3.

I claim:

The ornamental design for a tableware drying rack or similar article, substantially as shown and described.
